PROCESS OF AND APPARATUS FOR SIZING OR CLASSIFYING COMMINUTED MATERIAL.

1,196,048.

Specification of Letters Patent. Patented Aug. 29, 1913.

Original application filed February 5, 1914, Serial No. 816,754. Divided and this application filed October 6, 1915. Serial No. 34,742.

To all whom it may concern:

Be it known that we HENRY M. SUTTON, WALTER L. STEELE and EDWIN G. STEELE, citizens of the United States, residing at Dallas, in the county of Dallas and State of Texas, have invented certain new and useful Improvements in Processes of and Apparatus for Sizing or Classifying Comminuted Material, of which the following is a specification, reference being had therein to the accompanying drawing.

This invention relates to a process of and an apparatus for sizing or classifying comminuted material and is in the nature of an improvement upon our Patents #1,141,852, granted June 1, 1915, and #1,144,933 granted October 27, 1914, and comprises a division of our application Serial Number 816,754, filed February 5, 1914, whereby the particles are carried over a series of independently operated and adjustably mounted sizing units.

Another object of the invention is to provide a sizing surface consisting of a number of separate units; each unit of the series doing only a portion of the sizing, the last unit of the series completing the process and separately delivering the sized products.

Another and important feature of the invention, is the provision of means for transferring the particles from one sizing surface to the next succeeding one in approximately the same condition in which they left the said surface, and at a higher point on the next succeeding surface than would be the case were the particles allowed to take their natural path of travel from one sizing surface to the next.

We have found by experimenting, that when extremely close sizing is required, for instance such as is necessary to prepare certain kinds of ore pulp for the separation of their various constituents upon the usual form of concentrating or separating apparatus, that the sizing can be better accomplished on a number of separate units, as each unit acts upon the material independent of the other and the speed of the moving deck thereof, its speed of vibration and its inclination can be independently controlled, thus obtaining a closer and more accurate adjustment for the work to be accomplished.

Other and further objects and advantages

of the invention will be hereinafter set forth and the novel features thereof defined by the appended claims.

In the drawings—Figure 1, is a perspective of our improved construction of apparatus for carrying out the process of sizing a mass of comminuted material upon a series of sizing surfaces; Fig. 2, is an end view showing the relative position of the deflecting baffles to the several units of the apparatus; Fig. 3, is a diagrammatic view showing the travel of the particles of comminuted material through the deflecting baffles from one sizing surface to another. Fig. 4, is a transverse section through the corrugated belt having longitudinally arranged V-shaped grooves formed therein which gradually increase in depth toward its lower edge in order to increase the resistance of the material in its movement by gravity; Fig. 5, is a transverse section through a slightly modified form of belt; the corrugations and grooves of which are formed upon curved lines which increase in depth toward the lower edge thereof; the rounded grooves formed thereby offering less resistance to the material in its movement by gravity than the straight-sided grooves; Fig. 6 is a detail end view showing the relative position of the baffle to the sizing surface where it passes over the roll; Fig. 7 is a transverse enlarged section through one section of the apparatus showing one means of supporting the deck frame in order to change the inclination thereof; Fig. 8, is a perspective of a belt having longitudinally arranged grooves formed therein; Fig. 9, is a transverse enlarged section through the supporting surface or deck showing the agitating roller and in dotted lines, the movement imparted to said surface or deck by the rotation of said roller; and Fig. 10, is an end elevation of the agitating roller.

Like numerals of reference refer to like parts in the several figures of the drawings.

In the drawings, 1, 2, 3 and 4 indicate a series of deck frames arranged in stepped relation, and adjustably supported by depending curved slotted arms A through which extend threaded studs A' supported on the base A"; the studs being provided with hand wheels for clamping the arms in

adjusted position in a similar manner, as shown in our Patent #1,114,935, dated October 27, 1914, whereby each of the deck frames will be allowed to be adjusted independently in order to change the inclination thereof so as to adjust the inclination of the supporting surface carried thereby, which will be later described, whereby any one of the frames can be adjusted independently of the other to allow the classifying surface to be adjusted to suit the class of material being sized.

The deck frames are provided with suitable bearings at each end in which are mounted shafts 5 and 6 carrying rollers 7 and 8 on which are mounted endless flexible belts 9, 10, 11 and 12 arranged to deliver the material progressively from the upper belt to the lower belt. These belts are preferably provided with longitudinally arranged corrugations increasing in depth from the upper edge toward the lower edge thereof, but it is of course understood that any form of belt having a roughened surface can be employed for carrying out the process of sizing the material.

Each of the shafts 6 is provided with a pulley 13 over which passes the drive belt 14 driven by change-speed mechanism A substantially as shown in our companion Patent #1,114,935, in order that the speed of each belt can be controlled.

Mounted intermediate the shafts 5 and 6 in each of the deck frames, is a shaft 15 carrying an angular tapering roller 16 constructed substantially as disclosed in our Patent #1,114,935, dated October 27, 1914. The shafts 15 carrying the angular rollers 16 extend outwardly beyond the upper side bar of the respective frames and are provided with beveled gears 17 which mesh with beveled gears 18 carried by shafts 19 mounted in suitable bearings; said shafts carrying pulleys 20 over which pass drive belts 21 driven by a change-speed mechanism B constructed substantially as disclosed in our Patent #1,114,935, dated October 27, 1914, whereby the speed of vibration of the belts can be independently controlled.

The construction of the several units as hereinbefore described, is substantially the same and the description of one is sufficient for all, as each is operated in the same manner that the adjacent unit is operated, but is under an independent control and from the foregoing description, it will be seen that a sizing apparatus is provided composed of a number of units capable of being adjusted independently in order to change the inclination of the surface and that the speed of travel of the belt and the vibration thereof can also be controlled independently.

Arranged at the delivery end of each of

the sizing surfaces 9, 10 and 11, is a series of spaced deflecting baffles 22, disposed in such a position as to receive and deliver the sized particles from the upper sizing surface to the next lower sizing surface in such a manner that the particles are prevented from racing or bouncing.

The deflecting baffles 22 conform to the curvature of the roller over which the belts pass, but are spaced slightly therefrom and are arranged as clearly shown in Figs. 2 and 3 forming a number of channels which extend obliquely in order to receive the material and deliver the same to the next succeeding surface at a higher point, as will be later described. These baffles are preferably formed of angled plates supported by any suitable means, not shown, in the position as disclosed in Figs. 1, 2 and 3.

By constructing a sizing apparatus composed of a series of units, having deflecting baffles arranged to receive and deliver the material from one sizing surface to another, the particles are caused to travel a greater distance over the sizing surface than would be the case with an apparatus without the deflecting baffles, and by giving the baffles a crook at their lower ends, the movement of the particles is arrested when they are delivered to the sizing surface so as to prevent the same from racing or bouncing.

The division of these baffles into narrow channels facilitates the transfer of the particles from one sizing surface to the next succeeding surface without altering materially the degree of sizing, so far as the progress upon the preceding surface is concerned, and at the same time, the particles are advanced and delivered to the next succeeding surface at a higher point. This can be readily understood by referring to the diagrammatic view illustrated by Fig. 3, where the approximate inclination of the sizing surface is shown with reference to the perpendicular line K—K, the dotted line terminating at M showing the travel of the particles through the deflecting baffles.

The particle N on reaching the roller travels from the point 60 to 61 and thence to 62 on the next succeeding surface, and is delivered at the point M, while if it was allowed an unrestricted line of travel under the influence of gravity and the agitation of the sizing surface, it would report at L.

A suitable apron 23 is arranged at the delivery end of the sizing surface 12 and is provided with a spaced bar 24 under which are adjustably mounted fingers 25 for deflecting the sized particles delivered from the last sizing surface of the apparatus into suitable receptacles and it is of course understood that while we have shown such an apron for this purpose, the same can be dispensed with and the sized particles de-

livered directly into a number of receptacles.

A suitable hopper 26 is arranged to deliver material upon the upper sizing surface 9 and the line of movement over the respective sizing surfaces, is illustrated by the shaded lines in Fig. 1.

From the foregoing description, it will be seen that we have provided a process of and 10 an apparatus for sizing comminuted material in which the material is progressively subjected to the action of a series of sizing surfaces arranged at an inclination in order to subject the particles to the action of 15 gravity; each sizing surface having means for exerting a resistance to the material against the force of gravity and means for vibrating the surface in order to modify the resistance so as to allow the particles to 20 travel by gravity in lines deviating from the line of normal movement of the material, means being provided at the delivery end of each sizing surface, for conveying the particles and delivering the same on the adjacent sizing surface at a point above that at 25 which they are delivered from the preceding sizing surface.

In the specification, we have referred to the material as being advanced against the 30 force of gravity in its movement from one sizing surface to the adjacent surface, but it is of course understood that this movement is not wholly against the force of gravity but is a deflecting movement from 35 its normal path of travel in order to advance the material in its movement from one surface to the other. By this construction, the material delivered from one surface is deposited upon the next succeeding 40 surface at a higher point than would be the case, if the particles were allowed to drop by gravity.

What is claimed is:

1. The process of sizing material, consisting in transporting material composed of grains of varying sizes on a series of successive supports, and subjecting said material to gravitational impulses adapted to deviate the components of said material 45 from the direction of transport in proportion to their respective sizes, progressively varying the speed of transport upon the successive supporting surfaces, and separately collecting the separated sizes of material 50 from the last supporting surface.

2. The process of sizing material, consisting in supporting and transporting material composed of grains of various sizes on a series of successive continuously moving transversely inclined supporting surfaces to cause the particles to deviate from the line of transporting movement in proportion to their respective sizes, progressively varying the speed of transport upon 60 the successive supporting surfaces, and separately collecting the separated sizes of material 65 from the last supporting surface.

3. The process of sizing material consisting in supporting and transporting material composed of grains of varying sizes on a series of successive continuously moving supports inclined transversely to the direction of transporting movement to cause the particles to deviate from the line of 70 transporting movement in proportion to their respective sizes, progressively varying the speed of transport upon the successive supporting surfaces, and separately collecting the separated sizes of material from the 75 last supporting surface.

4. The process of sizing a mass of solid material consisting in progressively and continuously transporting material composed of grains of varying sizes on a series 80 of continuously moving transversely inclined supporting surfaces, and subjecting said material to the action of gravity to cause the particles to move transversely thereon in proportion to their respective 85 sizes, transferring said material in its distributed condition from one surface to the adjacent surface, so as to advance the material in its movement from one surface to the adjacent surface, arresting the movement of the material deposited from one 90 surface to the adjacent surface, progressively varying the speed of transport upon the successive supporting surfaces, and separately collecting the separated sizes of material 95 from the last supporting surface.

5. In a machine for sizing solid material, a series of continuously moving sizing surfaces arranged in line of continuous movement and inclined transversely to the direction of continuous movement, means for transferring material discharged from the end of one continuously moving surface in distributed condition to the opposite end of the adjacent surface at a higher point, 100 means for progressively varying the speed of travel of the successive continuously moving surfaces, and means for separately collecting the separated sizes of material 105 discharged from the last supporting surface.

6. The process of sizing material, consisting in transporting material composed of grains of varying sizes on a series of successive supports inclined transversely to the direction of transporting movement, delivering the material in distributed condition from one surface to progressively increased extents of the succeeding surface, progressively varying the speed of transport upon the succeeding surfaces, and separately collecting the separated sizes of material from 110 the last supporting surface.

7. The process of sizing material, consisting in transporting material composed of grains of varying sizes on a series of suc- 115

cessive supporting surfaces inclined transversely to the direction of transporting movement, and subjecting said material to progressively varying gravitational impulses adapted to deviate the components of said material from the direction of transport in proportion to their respective sizes, delivering the material in distributed condition from one surface to progressively increased extents 5 of the succeeding surface, progressively varying the speed of transport upon the successive supporting surfaces, and separately collecting the separated sizes of material from the last supporting surface.

15 8. The process of sizing material, consisting in transporting material composed of grains of varying sizes on a series of successive supporting surfaces inclined transversely to the direction of transporting movement, and subjecting said material to gravitational impulses adapted to deviate the components of said material from the direction of transport in proportion to their respective sizes, delivering the material in distributed 20 condition from one surface to progressively increased extents of the succeeding surfaces, progressively varying said gravitational impulses upon the successive supporting surfaces, progressively varying the speed of 25 transport upon the successive supporting surfaces due to delivery from one surface to the next, and separately collecting the separated sizes of material from the last supporting surface.

30 9. In a machine for sizing solid material, a series of independently adjustably mounted continuously moving sizing surfaces arranged in line of continuous movement and inclined transversely to the direction of continuous movement, means for transporting material discharged from the end of one continuously moving surface in distributed condition to progressively increased extents of the succeeding surface, progressively varying 35 the speed of travel of the successive continuously moving surfaces, and means for separately collecting the separated sizes of material discharged from the last supporting surface.

40 10. In a machine for sizing material, a series of continuously moving sizing surfaces arranged in line of continuous movement and inclined transversely to the direction of continuous movement, means for 45 transferring material in distributed condition from the end of one continuously moving surface to the next succeeding surface so as to advance the material in its transferring movement, progressively varying 50 the speed of travel of the progressively mov-

ing surfaces, and means for separately collecting the separated sizes of material discharged from the last supporting surface.

11. A machine for sizing material, composed of grains of varying sizes, comprising 65 a series of successive continuously moving supporting surfaces inclined transversely to the direction of the continuous movement, means for vibrating said surfaces to cause the components of said material to deviate 70 from the line of continuous movement in proportion to their respective sizes, means for transferring material in its distributed condition from one surface to progressively increased extents of the succeeding surface, 75 means for driving the successive continuously moving surfaces at different rates of speed, means for progressively varying the inclination of said surfaces, and means for collecting the different sizes of material discharged from the last surface.

12. A machine for sizing solid material, composed of grains of varying sizes, comprising a series of successive continuously moving supports inclined transversely to the 85 direction of continuous movement, means for vibrating said supports to cause the components of said material to deviate from the line of continuous movement in proportion to their respective sizes, means for progressively varying the speed of movement of 90 said supports, a series of spaced angled deflecting baffles arranged at the end of each of said supports for transferring material in its distributed condition from one surface to a higher point on the adjacent surface, and means for collecting the separate sizes of material from the last supporting surface.

13. In a machine for sizing solid material, 100 a series of laterally inclined and longitudinally progressing separating surfaces, means for transferring material in distributed condition from one surface to the adjacent surface so as to advance the material in its 105 transferring movement, mechanism for imparting agitative movement to said surfaces, progressively varying the speed of travel of the progressively moving surfaces, and means for separately collecting the separated 110 sizes of material discharged from the successive supporting surfaces.

In testimony whereof we affix our signatures in presence of two witnesses.
